(57) CLAIM

The ornamental design for a cosmetic product dispensing head, as shown and described.

DESCRIPTION

FIG. 1.1 is a perspective view thereof;

FIG. 1.2 is a front view thereof;

FIG. 1.3 is a back view thereof;

FIG. 1.4 is a left view thereof;

FIG. 1.5 is a right view thereof;

FIG. 1.6 is a top view thereof; and

FIG. 1.7 is a bottom view thereof.

The broken lines in the drawings depicting portions of the cosmetic product dispensing head are for illustrative purposes only and form no part of the claimed design.
